[57] CLAIM

The ornamental design for a light emitting helmet, as shown and described.

DESCRIPTION

FIG. 1 is a front elevational view of a light emitting helmet showing my new design.

FIG. 2 is a back elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The face shown in broken lines in FIGS. 1, 3, 4 and 5 is shown for illustrative purposes only and forms no part of the claimed design.
